UNITED STATES PATENT OFFICE

RUSSELL STOVER, OF DENVER, COLORADO

DESIGN FOR A BUNGALOW BOX

Application filed October 19, 1929. Serial No. 33,110. Term of patent 14 years.

To all whom it may concern:

Be it known that I, RUSSELL STOVER, a citizen of the United States, residing at Denver, in the county of Denver and State of Colorado, have invented a new, original and ornamental Design for Bungalow Box, of which the following is a specification, reference being had to the accompanying drawings, forming a part thereof, and wherein—

Fig. 1 is a face view or front elevational view of the box showing my new design.

Fig. 2 is an edge elevational view of the box.

Fig. 3 is a rear elevation of the bottom of the box, showing the contour of the containing portion of the box.

I claim:

The ornamental design for a bungalow box as shown.

In testimony whereof I affix my signature.

RUSSELL STOVER.
